UNITED STATES PATENT OFFICE.

PAULINA M. L. HERSE, OF BUFFALO, NEW YORK, ASSIGNOR, BY MESNE ASSIGNMENTS, TO JANE Y. HOWELL, OF SAME PLACE.

GRAIN AND COCKLE SEPARATOR.

SPECIFICATION forming part of Letters Patent No. 258,297, dated May 23, 1882.

Application filed April 25, 1881. (No model.)

To all whom it may concern:

Be it known that I, PAULINA M. L. HERSE, of the city of Buffalo, in the county of Erie and State of New York, have invented new and useful Improvements in Grain and Cockle Separators, of which the following is a specification, reference being had to the accompanying drawings.

This invention relates to that class of grain-separators which consist of a revolving cylinder provided on its inner surface with indentations, cells, or pockets in which the small grains embed themselves, and are elevated by the rotation of the cylinder above a trough arranged within the cylinder into which the small grains are discharged, while the grains which are too large to enter the pockets or cells roll back on the lower part of the ascending side of the cylinder, and are finally discharged over the tail end of the cylinder.

The object of my invention is to construct a machine of this class in which both oats and cockle are effectually separated from the wheat; and my invention consists of the mechanism whereby these results are accomplished, as hereinafter fully set forth.

In the accompanying drawings, consisting of four sheets, Figure 1 is a longitudinal section of a grain-separator provided with my improvements. Fig. 2 is a top plan view thereof. Fig. 3 is a horizontal section through the axis of the separating-cylinders. Figs. 4 and 5 are end views of the machine. Fig. 6 is a longitudinal vertical section, and Fig. 7 a horizontal section of a modified construction of the machine. Fig. 8 is a cross-section in line $z-z$, Fig. 6. Fig. 9 is a longitudinal fragmentary section of the separating-sieve. Fig. 10 is a fragmentary top plan view thereof with a portion of the perforated plate broken away.

Like letters of reference refer to like parts in the several figures.

A represents the stationary frame of the machine, and B C the separating-cylinders, arranged one behind the other in a slightly-inclined position in the frame A. The cylinders are preferably arranged in the same axial line, and secured together by a short cylinder, C', of slightly larger diameter. The cylinders B C are supported by means of rings or circular

flanges b upon grooved rollers d, which are secured to two parallel shafts, d' d'', journaled in bearings in the frame A. The shaft d is provided at its end with a bevel-wheel, D, which is driven by a bevel-pinion, D', mounted on a horizontal shaft, e, to which power is applied in any suitable manner, and whereby the cylinders are rotated in the direction of the arrow in Figs. 4 and 5.

The cylinder B is provided on its inner surface with cavities, cells, or indentations of a size which permits the round grains of cockle and similar small seeds to lie in these cavities and to be elevated by the rotation of the cylinder, while the larger grains of wheat are rejected and roll back on the inner surface of the cylinder. The cylinder C is provided on its inner surface with cavities, cells, or indentations of larger size, which permit the grains of wheat to lie in the cavities and be elevated by the rotation of the cylinder, while the larger grains of oats are rejected and roll back.

F represents an inclined separating-sieve, arranged above the cylinders B C, and supported in the frame A by means of elastic arms f. The sieve F is preferably provided with a straw-sieve, g, which is arranged above the sieve F, and whereby the straw, sticks, stones, and similar large foreign matter are separated from the grain, the latter passing through the meshes of the sieve, while the foreign matter is discharged over the tail end of the sieve. The sieve F is preferably composed of a sand-sieve, h, which permits only the fine sand to pass through its meshes, while the grain passes on to the next section, h', of the sieve F, which permits the smallest wheat and cockle and similar small grains and seeds to pass through its meshes, while the rest of the grain passes on to the last section, h'', which permits the larger wheat to pass through its meshes, while the largest wheat and oats pass over the tail of the sieve F. The small wheat, cockle, and small seeds, which pass through the second section, h', of the sieve F, fall upon the inclined bottom plate, i, of the sieve, and are conducted by a spout, I, to the cylinder B. The largest wheat and oats, which pass over the tail of the sieve, are conducted by a spout, K, to the cylinder C. The medium-sized wheat,

which passes through the section h^2 of the sieve F, falls upon an inclined bottom, l, and is conducted by a spout, L, to the grain-trough M of the cylinder C.

5 f' represents transverse stationary bars, rods, or wires, which are arranged underneath the sieve for the purpose of preventing the wheat and oats from lodging in the perforations of the sieve. The bars or wires f' are 10 arranged so closely together that the shaking motion of the sieve will bring each perforation over one of the bars or wires, and the latter are rearranged so closely to the under side of the sieve that they will come in contact with the point 15 of any kernel of grain which may have lodged in an opening and displace such kernel, as indicated in Fig. 9. The bars or wires f' do not offer any obstruction to the free passage of the round grains—such as cockle—through 20 the perforations of the sieve.

The sieve F and the grain-conduits attached thereto receive a shaking motion by an eccentric or crank, p, mounted on a transverse shaft, p' , and connected with the sieve by a rod, p^2 . 25 N represents the cockle-trough, arranged in the cylinder B, and n m the catch-boards connected with the troughs N M, respectively, in the usual manner.

n' is a conveyer arranged in the trough N 30 to deliver the cockle which is deposited in this trough at the outer or higher end of this cylinder, and m' is a conveyer arranged in the trough M to deliver the grain which is received in said trough at the outer or lower 35 end of this cylinder. The two conveyers n' m' are mounted upon the same shaft, which is driven by gear-wheels n^2 , or by any other suitable means.

o are depressed cups or pockets, which are 40 formed between the cylinders B and C in the short cylinder C', which connects the two cylinders. The grain which passes over the tail of the cockle-separator B falls into the pockets o , whereby it is elevated and deposited in 45 the grain-trough M of the oats-separator C.

o' is a circular flange or ring, arranged on the inner side of the cylinder C, between the latter and the pockets o , for the purpose of preventing the grain which is discharged from 50 the cylinder B from entering the cylinder C.

o^2 is a stationary partition, arranged at the tail end of the cylinder B, for preventing the wheat from returning into the cylinder B.

Q represents an ascending air-trunk, into 55 which the grain is delivered from a hopper or box, q, before the grain passes to the sieve F, and which is connected with the eye of a fan, R, by means of horizontal spouts q' q^3 and a chess-hopper, q^2 .

60 S is an ascending air-trunk, into which the grain is delivered from the trough M of the separating-cylinder C by a spout, s. The air-trunk S is connected with the eye of the fan R by horizontal air-trunks s' s^3 and a chess-hopper, s^2 . The fan is rotated by a belt, r, 65 from the shaft p' .

The operation of my improved machine is as follows: The grain is first spouted into the air-trunk Q, where it is freed by the air-current from the light impurities. The grain falls 70 from the trunk Q upon the sieve g, where it is freed from the straw, sticks, stones, and other large impurities. From the sieve g the grain passes upon the sieve F, where it is divided into three different grades, the first grade comprising the cockle and small wheat, the second middle-sized wheat only, and the third 75 large wheat and oats. The first grade passes into the cylinder B, where the cockle is separated from the wheat, the cockle being elevated and delivered into the trough N, from 80 which it is removed by the conveyer n' , while the wheat rolls back and escapes finally over the tail end of the cylinder. The third grade passes into the cylinder C, wherein the oats 85 are separated from the wheat, the latter being elevated and delivered into the trough M, from which it is discharged by the conveyer m' , while the oats roll back and escape over the tail of the cylinder C. The wheat which escapes over 90 the tail of the cylinder B is elevated by the pockets o and delivered into the trough M, where it is commingled with the wheat from the cylinder C, and the second grade of wheat 95 from the sieve F, which contains neither cockle nor oats, is also delivered into the trough M by the spout L, so that the conveyer m' discharges all the different grades of wheat together into the air-trunk S, when the light impurities which have been detached from the 100 kernels in their passage through the machine are separated from the grain by the air-current.

Instead of the pockets o , whereby the wheat is transferred from the cylinder B to the trough M, openings may be substituted, which permit the escape of the wheat from the tail end of the cylinder B; but this arrangement is not as desirable, because the wheat is then discharged at two different points. 110

The spouts I, L, and K are provided with valves t' , whereby the grain may be directed from one spout into another, so that if the grain operated upon should contain no cockle the small wheat, which passes through the section h' of the sieve F, can be delivered into the spout L and conducted by the latter directly to the grain-trough M of the oat-separator C without first passing through the cylinder B, and if the grain should contain no oats the third 115 grade of grain, which passes over the tail of the sieve F, can be directed into the spout L, and both the second and third grades delivered directly into the conveyer-trough M of the cylinder C. 120

Instead of arranging the two separating-cylinders one behind the other, they may be arranged side by side, as illustrated in Figs. 6, 7, and 8.

Although I prefer to divide the grain into 130 three different grades by the sieve F, it is not absolutely essential that this should be done,

since the grain may be divided into two grades, the small grain carrying the cockle with it and the large grain the oats.

I claim as my invention—

5 1. In a grain-separator, a cylinder composed of two or more sections arranged end to end and provided with cavities, cells, or indentations of different sizes, and independent discharge mechanism for each section of the cylinder, substantially as set forth.

10 2. The combination, with the cylinder B, provided on its inner surface with indentations, cells, or pockets which admit the cockle and reject the wheat, and the cylinder C, forming a continuation of the cylinder B, and provided on its inner surface with indentations, cells, or pockets which admit the wheat and reject the oats, of pockets or cups *o*, which are interposed between the cylinders B and C and receive the wheat from the cylinder B and deliver it into

the wheat-discharge trough of the cylinder C, substantially as set forth.

15 3. The combination, with the cylinder B, provided on its inner surface with indentations, cells, or pockets which admit the cockle and reject the wheat, and the cylinder C, provided on its inner surface with indentations, cells, or pockets which admit the wheat and reject the oats, of a preliminary grading apparatus, whereby the grain is divided into three different 20 grades according to size, and mechanism whereby the smallest grains are delivered into the cylinder B, the largest grains into the cylinder C, and the medium-sized grains into the wheat-discharge trough of the cylinder C, substantially as set forth.

PAULINA M. L. HERSE.
